UNITED STATES PATENT OFFICE.

FAYETTE S. ROBINSON, OF BOSTON, MASSACHUSETTS.

IMPROVEMENT IN LAMP-BURNERS.

Specification forming part of Letters Patent No. 121,550, dated December 5, 1871.

To all whom it may concern:

Be it known that I, FAYETTE S. ROBINSON, of Boston, county of Suffolk and State of Massachusetts, have invented certain new and useful Improvements in Lamp-Burners, of which the following is a specification:

The nature of my invention consists: First, in arranging the tube and its adjuncts in such a manner that the tube may be swung laterally in the plane of its width, so that the upper end of it, together with the burning part of the wick, may be adjusted to the orifice of the draught-plate or cone. Second, in several features of construction, which will be best understood by reference to the specification and drawing.

Figure 1 is a section of my invention. Fig. 2 is a plan of the same.

The lower part or support B of my burner is stamped up as represented in Fig. 1, and is attached to the principal plate H H' H. The central portion H' is perforated so as to allow a free circulation of air, and its outer rim is turned up, as shown in Fig. 1, and is provided with a spring-catch, L, Fig. 2, which, in connection with the lug M, serves to hold the chimney-ring K in position. This chimney-ring K has its outer edge turned up, as shown in Fig. 1, and fits closely into the plate H, and has a large central opening, and serves as a support for the draught-plate E, which is connected to it by standards k k.

By having a large central opening in the ring K K, and by holding it in position by its outer edge, I am enabled to support the draught-plate E independently of the wick-tube, and as the chimney is held by the ring K K and draught-plate E, I am enabled to remove and replace it, together with the ring K and draught-plate E, without having any part come near to the tube or wick, and thus become coated with oil and cinders.

The flame-orifice in my draught-plate terminates in depressions e f in the plate, which depressions bring the plate down to its proper position above the tube and near enough to the edges to cause the flame to spread well. The tube A passes through the lower portion of the base B, fitting closely, but arranged so the upper

part of the tube may swing back and forth in the plane of its width, the orifice in the plate H' being elongated so as to admit of this. The lower end of the tube A is so formed that it will fit the orifice in the base B and yet be free to swing. This is effected by forming projections near the lower end to rest upon the inside of the base-plate and by bending the lower ends of the sides of the tube outward, thus preventing any longitudinal motion of the tube. The tube A is provided with a link, N, which is pivoted to the clasp O, O being made fast to the tube. D is a screw working in the end of the link N, and collared at d, when it passes through the base B, so that it cannot move longitudinally; hence, as the screw D is revolved it will cause the link N and the tube A to move. C represents the feeding device, and is made in the usual manner.

By the use of the movable tube I avoid the too frequent retrimming now found necessary, and can carry a larger flame with more light and less offensive odors, and with less liability of breaking chimneys.

By supporting the draught-plate upon a movable base with open center, as described, and securing it in its place by holders instead of making it part of the burner, it can be instantly removed without disturbing the wick, and thus secure great advantage in cleaning, trimming, and lighting.

The advantage of two separate sets of holders for holding the cone and chimney is, it allows of releasing the cone from its seat and removing the cone and chimney together.

The base-ring K, to which the draught-plate E is attached, is held firmly in position by the lug M and catch L, while the chimney is held by an independent set of fastenings. This set of fastenings may consist of a screw, P, and the projection Q Q, or of a spring-catch, my idea being to hold the chimney by a set of fastenings that are independent of the fastenings for holding the parts of the burner together.

I do not confine myself to any particular mechanical construction of my improved burner, as that may be varied to suit the style of lamp or the manufacturer.

I claim as my invention—

1. The adjustable tube A, in combination with a lamp-burner, arranged substantially as described, for the purpose set forth.

2. The combination of the screw D, base B, link N, and movable tube A, substantially as described, and for the purpose set forth.

3. The base-ring K, standards *k k*, and draught-plate E F provided with chimney-fast-

enings Q Q and P, in combination with the plate H H' provided with fastenings M and L, substantially as described, and for the purpose set forth.

FAYETTE S. ROBINSON.
